CLAIM

The ornamental design for a building tool as shown and described.

DESCRIPTION

FIG. 1 is a perspective view of a building tool;

FIG. 2 is a top plan view thereof;

FIG. 3 is a bottom view thereof;

FIG. 4 is a first side elevation view thereof;

FIG. 5 is a second side elevation view thereof;

FIG. 6 is a front elevation view thereof; and,

FIG. 7 is a rear elevation view thereof.

The broken lines shown in the drawings represent portions of the article that form no part of the claimed design.
